[57] CLAIM

The ornamental design for an apparatus for selecting eyeglass frames, as shown.

DESCRIPTION

FIG. 1 is a front perspective view of an apparatus for selecting eyeglass frames showing my new design.

FIG. 2 is a back perspective view thereof.

FIG. 3 is a front elevation view thereof.

The words, numbers and wavy lines shown in FIG. 3 of the drawings have been omitted from FIG. 1 for purposes of clarity.

FIG. 1.

FIG. 2.

FIG. 3.
